UNITED STATES PATENT OFFICE

JOSEPH RICE, OF CHICAGO, ILLINOIS, ASSIGNOR OF ONE-HALF TO ELEVATOR COMPANY OF AMERICA, OF CHICAGO, ILLINOIS, A CORPORATION OF ILLINOIS

ELEVATOR CONTROL DEVICE

Application filed September 30, 1929. Serial No. 396,174.

My invention relates to elevators and has for its principal purpose an improvement in smoothness in operation particularly in changes of speed of the elevator by the employment of an inertia governing device.

In the operation of elevators, if they are accelerated or slowed down suddenly either in starting or stopping or in intermediate speeds, the resultant strain on the mechanism is very great and the discomfort to passengers in the elevator and danger of injuring are also great.

My invention contemplates the elimination of these difficulties by the provision, in combination with the cable sheave shaft, of an inertia governing device which tends to oppose changes in speed of the elevator at all times and thus makes these changes less abrupt.

My invention also contemplates as a more limited object the elimination of backlash in geared drives for elevators.

Other beneficial objects accomplished by this invention include improvements in accuracy and smoothness of floor stops, smoother operation in changes in speed where a two-speed power unit is employed, the elimination of the necessity for certain starting control devices on the driving motor, and the maintenance of the entire equipment in better condition by reduction of strains due to jerks in starting and stopping the elevator.

I will describe one form which the invention may take by reference to the accompanying drawings wherein—

Fig. 1 is a side view of an elevator driving mechanism equipped with my invention;

Fig. 2 is a view taken on the line 2—2 of Fig. 1; and

Fig. 3 is a reduced view taken at right angles to Fig. 1 as indicated by the line 3—3 of Fig. 1.

Referring now in detail to the drawings, I have not shown the elevator car or its connection to the driving mechanism as these are of well-known construction and form no part of the present invention.

The cables, by means of which the elevators are moved, operate upon the cable drum or sheave which is carried upon a shaft 6 mounted in suitable bearings as at 7 and 8.

In the embodiment shown, the drive shaft 6 which operates at a relatively low speed say in the neighborhood of 40 R. P. M. is driven from a prime mover 9 in the form of an electric motor usually of the alternating current squirrel cage type. In some of the installations made, they have the speed of about 1000 R. P. M. The motor is geared directly to the shaft 6 by means of shaft 10, worm 11, and worm gear 12 shown most clearly in Fig. 3. In this manner the sheave 5 is rotated to move the elevator up and down.

There is provided upon the shaft 10 a brake drum 13 and cooperating brake shoes as indicated at 14 to form a drum brake utilized in stopping the elevator. However, if only such a brake is used, the play between the worm and gear 11 and 12 gives a considerable amount of backlash in stopping which results in communicating a sudden jar or blow to the sheave 5 and through this and the operating cable to the operating car. Moreover, any sudden change in speed of the driving motor is directly communicated through the sheave 5 to the elevator car. It has been proposed to utilize a braking device upon the shaft 6 in the nature of a drum brake, but, owing to the relatively low speed of the shaft 6, such a braking device is not very successful in eliminating the jars and jerks due to backlash and changes in speed; and the brake of itself brings another disturbing effect, because in bringing the car to a stop the application of this brake to the slow moving shaft 6 usually results in the gripping of the drum 13 by the brake shoes after the speed has reduced to a certain point and thus again jerking the car in stopping.

In order to eliminate this jerking and strains on the mechanism, I provide a relatively high speed rotating device in conjunction with the shaft 6 which serves as an inertia governor to oppose sudden changes in the speed of the sheave 5. This inertia governor consists of a drum or wheel 15 mounted upon a shaft 16 which is connected for instance by means of the reduction gear composed of pinion 17 and gear 18 to shaft 6. One ratio of the speed of shaft 16 to the speed of shaft 6, which I have found very ef-

fective, is a ratio of approximately five to one. That is to say, for each revolution of shaft 6, the shaft 16 and its associated drum 15 must rotate five times. This is, of course, 5 only illustrative and any other ratio may be used so long as the speed of the inertia device 15 is sufficient to accomplish its purpose.

Now in starting up the motor 9, the drum 15 naturally will offer considerable opposition 10 due to its inertia and in this way too sudden a start is avoided because the drum 15 must be brought up to speed as the speed of rotation of shaft 6 increases. Having reached a definite speed, the drum 15 and 15 shaft 16 naturally oppose due to their inertia any change in speed; and, if for instance the brake 14 is applied, the backlash in the gears 11 and 12 will not seriously jerk or reduce the speed of the shaft 6 because 20 they will be opposed by the inertia of the high speed drum 15. Similarly any change in speed will be opposed by this inertia governing device.

In order to further insure the safety of the 25 elevator and aid in making quick stops without inconvenience or discomfort in the elevator, I provide in conjunction with the drum 15 a second braking means consisting of the brake shoes indicated at 19 and operated by 30 suitable control mechanism 20 which may be of any suitable type. In stopping the car, therefore, both brakes 14 and 19 may be applied to slow down the shaft 6. Both brakes being applied through the reduction gearing 35 to shaft 6, the shaft will naturally be reduced to a very low speed before the speed of the drums 13 and 15 is lowered sufficiently to permit the shoes to grip the drums and stop them suddenly.

40 I have found that by the use of this device much smoother acceleration and deceleration of the elevator will be obtained, and that owing to the elimination of jerks and jars the entire mechanism remains in condition much 45 better than it does without the device.

I have also found that, while it is good 50 practice to employ a primary resistance in the circuit of the squirrel cage motor where the car speed is greater than seventy-five feet per 55 minute to avoid jerks in starting, such precautions are not necessary when the present invention is employed because the inertia of the drum 15 opposes the torque developed by the motor and assures a smooth start.

56 As an example of the effect of the dual braking control in combination with the high speed drum 15, I have found that it is possible to stop the sheave 5 running free by the 60 use of both brakes within a quarter turn of the sheave after they are applied. With the brake 14 not used, the brake on the drum 15 stops the sheave within three-fourths of a turn, while, if the sheave is allowed to run with the motor shut off, it requires three turns 65 before it will stop. This gives a very good

comparison of the relative effects of the braking device.

Another advantage that has been noted in the use of this invention lies in the fact that, 70 when a two-speed motor is used and the current is shut off while changing from one speed to another, the inertia governing device maintains the speed of the elevator with but very little drop during the short interval required to change from one speed to the other 75 and eliminates any jerks due to the shifting of speeds.

While I have described one specific form of the invention, it is obvious that various 80 modifications may be made therein without departing from the scope of the invention. It is believed that from the above description the construction and operation of the device will be clear to those skilled in this art.

Having thus described my invention, what 85 I claim as new and desire to secure by Letters Patent is:

1. A drive mechanism for elevators and the like comprising a relatively high speed prime mover, a drive shaft having connection with said prime mover whereby it is driven therefrom at a reduced speed, and a stabilizing rotatable member positively connected to said drive shaft to be driven therefrom at high speed.

2. A drive mechanism for elevators and the like comprising a relatively high speed prime mover, a drive shaft having connection with said prime mover whereby it is driven therefrom at a reduced speed, and a stabilizing rotatable member positively connected to said drive shaft to be driven therefrom at high speed, 100 said member having a brake cooperating therewith whereby to stop said shaft.

3. A drive mechanism for elevators and the like comprising a relatively high speed prime mover, a drive shaft having connection with said prime mover whereby it is driven therefrom at a reduced speed, and a stabilizing rotatable member positively connected to said drive shaft to be driven therefrom at high speed, 105 said prime mover and said member having brakes thereon for stopping said shaft.

4. In a device of the character described, a 110 high speed prime mover, a drive shaft having a cable drum thereon, a worm and gear connection between the prime mover and drive shaft whereby to operate the drive shaft at a low speed, a second shaft having a positive drive connection with said drive shaft whereby it is driven at high speed from said drive shaft, and a fly-wheel on said second shaft.

5. In a device of the character described, a high speed prime mover, a drive shaft 125 having a cable drum thereon, a worm and gear connection between the prime mover and drive shaft whereby to operate the drive shaft at a low speed, a second shaft having a reducing gear connection with said drive 130

shaft whereby it is driven at high speed from said drive shaft, and a fly-wheel on said second shaft.

6. In a device of the character described, a high speed prime mover, a drive shaft having a cable drum thereon, a worm and gear connection between the prime mover and drive shaft whereby to operate the drive shaft at a low speed, a second shaft having a reducing gear connection with said drive shaft whereby it is driven at high speed from said drive shaft, a fly-wheel on said second shaft, and a braking means for said fly-wheel.

7. In an elevator power unit including a motor, a drive shaft geared to said motor to rotate at slow speed, and a cable sheave on said shaft, means for preventing sudden changes in the speed of rotation of said sheave comprising a shaft having a wheel thereon, and means connecting said shafts for driving said last named shaft at high speed from said drive shaft.

8. In an elevator power unit, a cable sheave, a shaft upon which said sheave is mounted, a motor shaft geared to said shaft for driving said sheave, a third shaft geared to said first named shaft by a reduction gear so as to be driven therefrom at a much higher speed, said third shaft having a fly wheel and a drum brake thereon.

9. In an elevator power unit, a cable sheave, a shaft upon which said sheave is mounted, a motor shaft geared to said shaft for driving said sheave, a third shaft geared to said first named shaft by a reduction gear so as to be driven therefrom at a much higher speed, and drum brakes on said motor and third shafts.

10. In a driving mechanism for elevators and the like including a drive shaft and a prime mover for rotating said shaft, an inertia governing device for smoothing out the operation of the elevator during changes in speed and direction comprising a rotatable drum positively connected to said shaft through a reduction gearing giving the drum a speed more than three times as great as the speed of the shaft.

In witness whereof, I hereunto subscribe my name this 20th day of Sept. A. D. 1929.

JOSEPH RICE.
